COMBINED TOOTHBRUSH HOLDER AND TOOTH PASTE DISPENSER

Joseph R. Simone, Phillipsburg, N. J.

Application June 29, 1956, Serial No. 42,088

Term of patent 3½ years

(Cl. D4—3)

FIG. 1.

FIG. 2.

Figure 1 is a perspective view of a combined toothbrush holder and tooth paste dispenser, showing my new design, looking from the top and at one side and end thereof; and

I claim:

The ornamental design for a combined toothbrush holder and tooth paste dispenser, as shown.
